UNITED STATES PATENT OFFICE

171,057

STAPLE DRIVING MACHINE

Fredrick W. Schmidt, Haworth, N. J., assignor to
Lou Obstfeld, Brooklyn, and Abraham Obstfeld,
New York, N. Y.

Application September 13, 1952, Serial No. 21,446

Term of patent 7 years

(Cl. D74—1)

To all whom it may concern:

Be it known that I, Fredrick W. Schmidt, a citizen of the United States, and a resident of Haworth, in the county of Bergen and State of New Jersey, have invented a new, original, and ornamental Design for a Staple Driving Machine, of which the following is a specification, reference being had to the accompanying drawing, forming a part thereof, wherein:

Fig. 1 is a side elevational view of a staple driving machine, embodying my new design;

Fig. 2 is a top plan view;

Fig. 3 is a front end view; and

Fig. 4 is a rear end view.

I claim:

The ornamental design for a staple driving machine, substantially as shown.

FREDRICK W. SCHMIDT.
